(57) **CLAIM**

The ornamental design for a beverage dispenser, as shown and described.

DESCRIPTION

FIG. 1 is a front view of a beverage dispenser showing my new design;

FIG. 2 is a right side view thereof, the left side view being a mirror image thereof;

FIG. 3 is a rear view of the beverage dispenser.

FIG. 4 is a bottom view of the beverage dispenser.

FIG. 5 is a top view of the beverage dispenser taken along the line 5—5 shown in FIG. 1; and,

FIG. 6 is a perspective view of the beverage dispenser. The broken lines in the drawings are for illustrative purposes only and form no part of the claimed design.
